UNITED STATES PATENT OFFICE.

JOSEF ESSER, OF MÜNCHEN-GLADBACH, GERMANY.

ELECTRICAL STATION-INDICATING SYSTEM.

No. 839,376.

Specification of Letters Patent.

Patented Dec. 25, 1906.

Application filed December 27, 1904. Serial No. 238,429.

To all whom it may concern:

Be it known that I, JOSEF ESSER, a citizen of the Empire of Germany, residing at München-Gladbach, in the Empire of Germany, have invented a new and useful Electrical Station-Indicating System, of which the following is a specification.

My invention relates to an electrical system in a railway-train for showing to the travelers in the several carriages or in their compartments the names of the different stations a sufficiently long time before the arrival of the train at the respective station. This electrical system comprises a sender under the charge of the conductor, a series of receivers in the different carriages or compartments, and a series of lines connecting the sender with the receivers. Each receiver is inclosed in a box on the wall or on the ceiling and is arranged to show in a window the name of any station in large distinctly visible characters. There are, it is true, known electrical station-indicating systems in which the sender comprises several adjustable sign-bearers for the different letters of a station-name, and the receivers are arranged to print characters similar to those adjusted on the sender one by one on a continuous strip of paper. My new system, however, differs from these old systems in that also the several receivers are each provided with adjustable sign-bearers corresponding to those of the sender; further, that separate branch systems connect the sign-bearers of the receivers with those of the sender and that a main line and a main return connect the several branch systems with a battery. My new system is so arranged that the several sign-bearers on the sender are first adjusted by the conductor and then a clockwork is wound up, and thereby put in motion, so that consecutive impulses are sent through the several branch systems for actuating the sign-bearers of all the receivers until they are all respectively adjusted in correspondence with the sign-bearers of the sender, when the receivers will all show in their windows the correct name of the next station.

I will now proceed to describe my invention with reference to the accompanying drawings, in which—

Figure 1 is an elevation of the first compartment of the sender, which contains a

sign-bearer and the clockwork in combination with the winding-on mechanism. Fig. 2 is a front view of the same. Fig. 3 is a rear view of the same. Fig. 4 is a vertical section through the same on the line A-B in Fig. 2. Fig. 5 is a similar vertical section through the lower part of a certain intermediate compartment of the sender, only certain parts being shown. Figs. 5^a and 5^b are details, which will be referred to later on. Fig. 6 is a view similar to Fig. 5, only other parts being shown for the sake of clearness. Fig. 7 is a vertical section through the box of a receiver and a side view of the latter. Fig. 8 is a rear view of three neighboring compartments of the receiver. Fig. 9 is a diagram of the system comprising a sender and three receivers, seen from the front; and Fig. 10 is a side view of the same.

Similar characters of reference refer to similar parts throughout the several views.

The sender under the charge of the conductor is marked S in Fig. 9 and comprises a frame with a series of compartments, the number of which is equal to that of the letters of the longest name of a station. In Fig. 9 I have shown nineteen compartments; but this number may be increased or decreased, according to the circumstances. A horizontal axle 1, Figs. 1 to 4, is fastened in the frame and passes through all the compartments. In each compartment a drum 3, a scroll 2, and a ratchet-wheel 79 are mounted to turn on the axle 1 and are rigidly connected with each other. A pawl 80 on the frame engages in the ratchet-wheel 79 for holding the drum 3 in any position, and the teeth of the ratchet-wheel 79 are so formed that the drum 3 may be turned in either direction, while the pawl 80 rides over the teeth until the drum 3 stops. Preferably the drum 3 is provided with a roughened border 4, by means of which it can be easily turned by hand. The circumference of each drum 3 is provided with the letters of the alphabet, marks of punctuation, and a blank space. Each scroll 2 has a plurality of concentric steps, which are arranged in a spiral line, so that the radius of the steps continuously and uniformly decreases from the most distant step down to the step nearest to the axle 1. The number of these steps is equal to that of the letters, the marks of punctuation, and the blank space on the periphery of the drum.

3, also equal to the number of the teeth of the ratchet-wheel 79. A rule 90, fastened on the frame, passes along the several drums 3 and serves for adjusting the same. An axle 5 7 and a rod 8 are fastened in the frame and pass through all the compartments. In each compartment a counting-lever 5, with a rear arm 6, is mounted to rock on the axle 7 in the plane of the scroll 2 and is given the tendency of turning in the direction of the arrow 9 in Fig. 1 by a helical spring 91, the one end of which is fastened on the lever, while its other end grasps the rod 8. The counting-lever 5 is provided with a pendent projection, which may rest on either step of the scroll 2 and is beveled off, so that it is enabled to ride over the steps of the scroll 2, while overcoming the tension of the spring 91 should the drum 3 be turned in the direction 10 of the arrow 19 in Fig. 1. In this case the projection of the counting-lever 5 can ascend from the step of the smallest radius to the step of the largest radius. If, on the contrary, the drum 3 is turned in a direction 15 opposite to that of the arrow 19, of course the projection of the counting-lever 5 will slide off the several steps under the action of the spring 91 until it strikes against the face of the scroll 2, which connects the two extreme steps. The lower arm 6 of the counting-lever is formed to a bent rack 12, in which the teeth 10 and 11, Figs. 5 and 6, of two pawls 13 and 15, respectively, can engage. All the pawls 13 are two-armed and 20 rock on a shaft 17, passing through all the compartments. A shaft 18 is mounted to turn in the frame and passes through all the compartments and carries in each compartment an eccentric on which the pawl 15 can 25 turn. This shaft 18 is driven by a clock-work, hereinafter described, in the direction of the hands of a watch when looked at in Figs. 1 and 4. It will be now understood that during a revolution of the shaft 18 the pawl 15, which is weighted by its bent rear arm 16, will move, say, from left to right, so that its tooth 11 will ride over the respective tooth of the rack 12, until it engages in the following space, and then the pawl 15 30 will move from right to left and turn the counting-lever 5 and arm 6, so that the tooth 10 of the other pawl 13 rides over the respective tooth of the rack, until it engages in the following space. The number of the teeth 35 of the bent rack 12 is equal to that of the steps of the scroll 2, and the eccentric on the shaft 18 is adapted for feeding the rack 12 one tooth after the other. When the tooth 11 of the pawl 15 has engaged in the last 40 space of the rack 12 on the right in Figs. 1 and 4, it will cease feeding the rack 12 and simply move to and fro a little. Beneath all the rear arms of the pawls 13 of either half of the sender S passes a tube 55, which is 45 fastened on the upper end of a lever 53, Fig. 50 55, rocking on a pin 52 in an intermediate compartment. There are two such intermediate compartments in the sender, and consequently two tubes 55 in the same center line.

When in a manner to be presently described the two levers 53 are turned through a small angle upward, the two tubes 55, carried by these levers, will raise all the rear arms of the pawls 13, and thereby simultaneously disengage all the teeth 10 of the pawls 13 from the bent racks 12. Beneath the rear arms 16 of the other pawls 15 of either half of the sender also a tube 51 passes, which is fastened on the upper arm 50 of a two-armed lever rocking on a pin 48 in the intermediate compartment. This arm 50 is provided with a pin 54, which engages in a recess of the lever 53 already referred to. A shaft 41 is mounted to turn in the frame 55 and passes from the end of the sender shown at Fig. 1 through the greater part of the whole length to the second intermediate compartment. In the two intermediate compartments this shaft 41 has fastened on it two disks 46, in the notches 47 of which the lower arms 49 of the two levers 49 50 normally engage. When in a manner to be described later on the shaft 41 is turned in the direction of the arrow in Fig. 6, the two 60 lower arms 49 will get out of the notches 47 of the two disks 46. In other words, they will be depressed, so that the two upper arms 50 will be turned upward and lift through the two tubes 51 all the rear arms 16 of the 65 pawls 15, and thereby withdraw all the teeth 11 from the bent racks 12. At the same time the pins 54 of the two upper arms 50 will have turned the two levers 53 upward through a small angle and lifted through the 70 two tubes 55 all the rear arms of the pawls 13, and thereby withdrawn all the teeth 10 from the bent racks 12. The latter being thus released, all the springs 91 will turn all the counting-levers 5 and arms 6 in the direction of the arrow 9 in Fig. 1 until the projections of all the counting-levers 5 strike the respective steps of all the scrolls 2. 75

The rear arms of all the pawls 13 are each rigidly connected with an elastic contact-arm 14, which is insulated from the pawl 13 by means of a disk 20 of insulating material. All the elastic contact-arms 14 engage in bent contact-springs 21, which are preferably made turnable on the frame and are in any known manner arranged to be simultaneously turned upward at will into, say, a horizontal position by means of a handle or the like, so as to bring them out of the paths of the elastic contact-arms 14. On turning all 80 the bent contact-springs 21 downward into their normal position (shown at Figs. 1, 4, 5, and 6) all the contact-arms 14 will be enabled to come in contact with the respective contact-springs 21 for closing branch cir- 85

cuits, hereinafter described, each time when the teeth 10, riding over the teeth of the bent racks 12, are depressed.

Fastened on the shaft 41 in the two intermediate compartments are also two disks 57 besides the two disks 46 already mentioned. Each of these disks 57 has a notch 56, in which the arm 59 of a circuit-changing switch rocking on the pin 48 normally engages under the action of a leaf-spring 60. The other arm 58 of this switch is connected with the free end of a doubly-bent contact-spring 61 (see Figs. 5^a and 5^b) and is insulated therefrom by means of a piece 92 of insulating material. When released, the doubly-bent contact-spring 61 comes in contact with another bent contact-spring 63 above, (see Fig. 5^b), and the two contact-springs 61 and 63 are disposed on a pillar 62.

Normally the arm 58 of the circuit-changing switch detaches the free end of the contact-spring 61 from the upper contact-spring 63 and rests on the intermediate part of the lower contact-spring 61. (See Fig. 5^a.) The circuit-changing switch 58 59 is insulated from its pin 48 and is electrically connected with the elastic arm 14 by a yielding line 85, so that normally impulses may be sent through the line 82, the contact-spring 61, the switch 58, the line 85, the contact-arm 14, the contact-spring 21, and the line 86. If, however, the contact-spring 21 is turned upward out of the reach of the contact-arm 14 and if the arm 59 of the circuit-changing switch is depressed, the current can only pass through the line 82, the two contact-springs 61 and 63, Fig. 5^b, and the line 83. In each intermediate compartment the two disks 46 and 57 are set at such a slight angle to each other that on turning the shaft 41 in the direction of the arrow in Fig. 6 first the arm 59 of the circuit-changing switch is depressed by getting out of the notch 56 of the disk 57, so as to change the circuit, and afterward the arm 49 of the two-armed lever 49 50 is depressed by getting out of the notch 47 of the disk 46, so as to release all the bent racks 12 from the teeth 10 and 11 of their pawls 13 and 15, respectively.

In the first compartment of the sender S (shown at Figs. 1 to 4) a spring-barrel 22 is mounted to turn on a shaft and is arranged to drive a clockwork with the fly 24, and thereby also to drive the shaft 18 already mentioned above. Within the first compartment also a cam 43 is fastened on the shaft 41 and is arranged to strike the pin 44 of a lever 45, fastened on a shaft 31. This shaft 31 is mounted to rock in the frame and extends to without and has fastened on it a detent 36 within and two levers 33 and 29 without. The detent 36 is arranged to stop and to release the fly 24. Fastened on the external end of the shaft 18 is a disk 35, on the periphery of which the pin 32 of the lever 33

can ride until it engages in a notch 34. The spring-barrel 22 is connected with its shaft by a spring, as usual, and carries two pins 25 25 on opposite sides of the shaft. These two pins 25 25 can strike one after the other the teeth of a curb-wheel 26, fastened on a shaft which is mounted to turn in the frame and carries without a locking-wheel 28. The latter is provided with a cut 27, (shown in Fig. 1,) in which a pin 30 on the lever 29 can engage. The pin 30 is a little beveled off and is connected with its lever 29 by means of a leaf-spring in such a manner that it can yield and get out of the cut 27 on the lever 29 being turned upward. As long as the pin 32 of the lever 33 rides on the periphery of the disk 35 the pin 30 is held out of contact with the disk 28 and is thus prevented from engaging in the cut 27. The curb-wheel 26 or the disk 28 is in any known manner prevented from shifting—for example, by means of an elastic disk bearing on the frame. When the pin 32 of the lever 33 engages in the notch 34 of the disk 35, of course the lever 29 will partake in this motion; but its pin 30 will simply strike the periphery of the disk 28, while bending upward a little its leaf-spring. The shaft 18 continuing its revolution, the pin 32 will soon again get out of the notch 34 and move the pin 30 off the disk 28. Thus the two levers 33 and 29 are periodically rocked during the run of the clockwork until the spring-barrel 22 by either of its pins 25 25 and the curb-wheel 26 turns the disk 28 at such a moment, at which the pin 30 engages in the cut 27, so that the detent 36, partaking in the motion of the two levers 33 and 29, stops the fly 24, and thereby the clockwork.

Fastened on the external end of the shaft of the spring-barrel 22 are a gear-wheel 38 and a pinion 39. This pinion 39 meshes with a gear-wheel 40, fastened on the shaft 41. A key-shaft 23 is mounted to turn in the frame and has fastened on it a gear-wheel 37, which meshes with that, 38, already mentioned. The clockwork is so arranged that the eccentric-shaft 18 may make a number (for example, thirty) of revolutions, which number is equal to or slightly larger than that of the steps of each scroll 21 before the fly 24 is stopped.

Each receiver (marked R in Fig. 9) comprises as many compartments as the sender S. On two axles 93 and 94, passing through all the compartments, two drums 64 and 65, Fig. 7, respectively, are mounted to turn in each compartment. The upper drum 64 is elastically connected with the frame by a helical spring 67, surrounding the shaft 93 and fastened with its one end on the frame and with its other end on the drum. A strip 66, of paper or other material, connects the two drums 64 and 65 and carries the same signs in the same order as each drum 3 of the sender S. (See Fig. 8.) The lower drum 65

is rigidly connected with a ratchet-wheel 68, in which two pawls 74 and 69 can engage. The one pawl 74 is mounted to turn on a pin 95 on the frame and is provided with a rear arm 96, which latter is overbalanced by a weight on the pawl, as is shown at Fig. 7. The other pawl 69 is pivotally connected with the bent free end of a lever 70 and is pressed by any known spring. The lever 70 is mounted to oscillate on a pin 71 and serves as an armature of a pair of electromagnets 72 72 in the respective compartment. It is pressed upward by a helical spring 75 and is thereby normally detached from the electromagnets 72 72, while at the same time the movable pawl 69 is withdrawn from the ratchet-wheel 68. It will be understood that each time when the two electromagnets 72 72 are energized they will attract the armature 70 and cause the pawl 69 to feed the ratchet-wheel 68 for moving downward the strip 66 through a distance of the signs. On the electromagnets 72 72 becoming without current the helical spring 75 will return the armature 70, with the pawl 69, to the initial position, while the pawl 74 checks the return motion of the strip 66 under the action of the spring 67. A braking-spring 73 is provided on the lever 70 for preventing the ratchet-wheel 68 from shifting. The receiver R is inclosed in a box 97 with a window 98. When the two drums 64 and 65 occupy their initial position, the blank space on the strip 66 will be opposite to the window 98. On feeding the strip 66 consecutively its different signs will appear one after the other in the window 98, and when the strip 66 ceases moving its last sign will be opposite to the window 98. While all the compartments of the receiver have each two electromagnets 72 72, only two pairs of electromagnets 78 78 are employed for simultaneously releasing all the pawls 74 from their ratchet-wheels 68. The two electromagnets 78 78 of each pair are arranged on the rear of two adjoining intermediate compartments. (See Figs. 8 and 9.) The two armatures 76 of the two pairs of electromagnets 78 78 are shown as pivotally connected with levers 99 on the frame and arranged to pull downward all the rear arms 96 by means of two tubes 100 in the same center line, whereupon all the drums 64 65 will be returned to their initial position by the springs 67.

Each compartment of the sender S is separately connected by a branch system with the corresponding compartments of all the receivers R, of which latter only three are shown in Figs. 9 and 10 for want of space. A single battery B is disposed for supplying the current to either branch system through the line 103 and the main line 104, which latter connects all the lines 82 in the several branch systems. (See Fig. 10.) Another main line 101 connects the lines 81 and 84 of all the

branch systems and serves for returning the current to the battery B through the line 102. The bent contact-spring 21 of the sender in each branch system is connected by a line 86 with the pair of electromagnets 72 of the last receiver, and the pairs of electromagnets 72 of the several receivers are connected one with another by lines 87 87, while the pair of electromagnets 72 of the first receiver is connected with the main return 101 by the line 81, already mentioned. The upper contact-spring 63 in each intermediate compartment of the sender is connected in series with the electromagnets 78 78 of the several receivers by lines 83 83, while the electromagnets 78 78 of the last receiver are connected by the line 84, already mentioned, with the main return 101. (See also Fig. 9.)

The electrical station-indicating system is operated as follows: At the commencement all the drums 3 of the sender S may occupy different positions, while the projections of all the counting-levers 5 either rest on the highest steps of the scrolls 2 or float in the air. The counting-levers 5 and arms 6 are prevented from turning by the teeth 10 and 11 of the two pawls 13 and 15, respectively, engaging in their bent racks 12. All the drums 64 and 65 of the different receivers R in general occupy different positions. Assuming the next station to be "Washington"—that is, a name with ten letters—the conductor will have to turn, say, the first ten drums 3 of the sender S in either direction and to so adjust them, with the aid of the rule 90, that all the letters of the name "Washington" will appear just above the rule 90. The consequence of this adjustment of the several drums 3 is that in every compartment the projection of the counting-lever 5 remains at a certain distance from the respective step of the scroll 2, on which it would rest if the bent rack 12 were released. Evidently the said distance equals the sum of the heights of the several steps of the scroll 2 when counting from the highest step, the number of these steps being equal to that of the consecutive signs on the periphery of the drum 3 until the desired sign appears just above the rule 90. Now the conductor turns all the springs 21 out of reach of the contact-arms 14 by means of a handle or the like, to open all the main circuits. He further applies his key to the key-shaft 23 and turns the latter to wind on the spring in the spring-barrel 22 by turning its shaft in the direction of the arrow in Fig. 1. Thereby of course the shaft 41 is also rotated. On turning the key-shaft first each circuit-changing switch 58 59 will be brought into the other position by the disk 57 for disconnecting the line 82 from the line 86 and connecting it with the line 83 by means of the two contact-springs 61 and 63. (See Fig. 5^b.) Afterward the two arms 49 will be depressed by their disks

46 for lifting the four tubes 51 51 55 55, and thereby releasing all the bent racks 12, whereupon the latter will be turned by the respective springs 91 in the direction of the arrow 9 in Fig. 1 until the projections of the counting-levers 5 strike the respective steps of the scrolls 2. Obviously the several counting-levers 5 and arms 6 will now occupy different positions. During the revolution of the shaft 41 the cam 43 will strike the pin 44 of the lever 45 and rock the shaft 31, with the detent 36 and the two levers 33 and 29. The detent 36 will release the fly 24, and the lever 29 will withdraw its yielding pin 30 from the cut 27 of the disk 28, and the pin 32 of the lever 33 will ride on the periphery of the disk 35. When about to complete the required number of revolutions of the key-shaft, first the two circuit-changing switches 58 59 and then the two levers 50 49 will return to their normal positions, so that all the lines 82 are again connected with the respective contact-arms 14, and the teeth 10 and 11 of all pawls 13 and 15, respectively, will again engage in the bent racks 12. The bent contact-springs 21 are now all returned to their normal positions by means of the handle or the like. The clockwork being now put in motion will rotate the shaft 18, with its eccentric, and thereby move all the pawls 15, so that the teeth 11 of the latter simultaneously feed the bent racks 12 one tooth after the other. The teeth 10 of all the other pawls 13 riding over the teeth of the bent racks 12 cause all the elastic contact-arms 14 to rock simultaneously, so that the latter periodically come in contact with the bent contact-springs 21, and thereby close all the main circuits. At each of these moments the battery B will send an impulse through the line 103, the main line 104, all the lines 82, the contact-springs 61, the circuit-changing switches 58, the lines 85, the contact-arms 14, the lines 86, the electromagnets 72 72 of the several receivers R R, and the intermediate lines 87 87; the lines 81, the main return 101, and back through the line 102. The electromagnets 72 72 being thus energized will attract their armatures 76 and disengage the pawls 74 from the ratchet-wheels 68, whereupon all the springs 93 of all receivers R R will return their drums 64 and 65 and strips 66 to the initial positions. Now the receivers R R will be ready for their actuation in the manner described above. It is evident that all the bent contact-springs 21 require to be brought out of the paths of the contact-arms 14 in the manner described above, so as to prevent the current from circulating in the main circuits at the moment when the secondary circuits are engaged for returning the parts of all the receivers R R to their initial position. Thereby all disorder is avoided.

The electrical station-indicating system may be varied in many respects without departing from the spirit of my invention.

What I claim as my invention, and desire to secure by Letters Patent, is—

1. In an electrical station-indicating sys-

sender S just above the rule 90. This will be clear when taking into consideration that the tooth 11 of the pawl 15 has engaged in as many teeth of the bent rack 12 as there are steps on the scroll 2 when counting from the highest step to that which the projection of the counting-lever 5 had struck.

Obviously all the counting-levers 5 and arms 6 will stop at different moments in correspondence with the positions of the signs on the drums 3, or, in other words, in correspondence with the letters of the name of the station to be indicated. The clockwork will, in general, stop a while after the last counting-lever 5 has reached its extreme upper position, the two pins 25 25 of the spring-barrel 22 having fed the curb-wheel 26 one tooth after the other and at last brought the cut 27 of the disk 28 into the path of the pin 30 on the lever 29, when this pin 30 will engage in the cut, so that the detent 36, partaking in the motion of the lever 29, will stop the fly 24. At this moment all the receivers R R will indicate in their windows 98 the same station as the sender S. As already said, all the counting-levers 5 of the sender occupy their extreme position, so that their projections either rest on the highest steps of the scrolls 2 or float in the air. When the conductor now adjusts all the drums of the sender S for another station-name in the manner described above and turns the key-shaft 23 to wind on the spring in the spring-barrel 22, first all the circuit-changing switches 58 59 will be brought into the other position and close all the secondary circuits. Then the battery B will send a current through the line 103, the main line 104, the respective lines 82, the contact-springs 61 and 63, the lines 83, the electromagnets 78 78 of the several receivers R R, and the intermediate lines 83 83, the lines 84, the main return 101, and back through the line 102. The electromagnets 78 78 being thus energized will attract their armatures 76 and disengage the pawls 74 from the ratchet-wheels 68, whereupon all the springs 93 of all receivers R R will return their drums 64 and 65 and strips 66 to the initial positions. Now the receivers R R will be ready for their actuation in the manner described above. It is evident that all the bent contact-springs 21 require to be brought out of the paths of the contact-arms 14 in the manner described above, so as to prevent the current from circulating in the main circuits at the moment when the secondary circuits are engaged for returning the parts of all the receivers R R to their initial position. Thereby all disorder is avoided.

The electrical station-indicating system may be varied in many respects without departing from the spirit of my invention.

What I claim as my invention, and desire to secure by Letters Patent, is—

1. In an electrical station-indicating sys-

tem, the combination with a sender under the charge of a conductor and comprising a series of adjustable and revoluble drums with signs on the periphery and with scrolls having concentric steps of consecutively decreasing radius in correspondence with the signs, counting-levers with toothed segments, springs pressing the counting-levers on the scrolls, movable pawls, means for periodically moving the movable pawls to feed the toothed segments one tooth after the other against the action of the springs, stationary pawls adapted to ride over the teeth of the toothed segments, means for simultaneously withdrawing the movable and stationary pawls from the toothed segments, contact-arms rigidly connected with the stationary pawls, contact-pieces, lines connecting the contact-pieces with the contact-arms, and other contact-pieces with which the contact-arms can come in contact, of a plurality of receivers in the several carriages of a train or their compartments and each comprising two series of revoluble drums, strips connecting the drums of the two series and carrying signs similar to those of the drums of the sender, springs for returning the drums of the one series to their initial positions, ratchet-wheels rigidly connected with the drums of the other series, stationary pawls, electromagnets with rocking armatures, movable pawls linked to the rocking armatures, springs for detaching the armatures from the electromagnets and withdrawing the movable pawls from the ratchet-wheels, and brakes for preventing the ratchet-wheels from shifting, further parallel lines connecting in series the corresponding electromagnets of the several receivers and the corresponding contact-pieces of the sender, a common line connecting the parallel lines at their ends, another common line connecting the other contact-pieces of the sender, a battery, and lines connecting the battery with the two common lines.

45. 2. In an electrical station-indicating system, the combination with a sender under the charge of a conductor and comprising a series of adjustable and revoluble drums with signs on the periphery and with scrolls having concentric steps of consecutively-decreasing radius in correspondence with the signs, counting-levers with toothed segments, springs pressing the counting-levers on the scrolls, movable pawls, means for periodically moving the movable pawls to feed the toothed segments one tooth after the other against the action of the springs, stationary pawls adapted to ride over the teeth of the toothed segments, contact-arms rigidly connected with the stationary pawls, shiftable contact-pieces with which the contact-arms can periodically come in contact, means for bringing the shiftable contact-pieces in and out of reach of the contact-arms, circuit-changing switches, lines connecting the cir-

cuit-changing switches with the contact-arms, contact-pieces, contact-springs bearing against the contact-pieces and connected at their free ends with the circuit-changing switches from which they are insulated and by which they are normally detached from the contact-pieces so that they normally bear against the circuit-changing switches, and means for moving the circuit-changing switches from the normal position to the other position and for simultaneously withdrawing the movable and stationary pawls from the toothed segments, of a plurality of receivers in the several carriages of a train or their compartments and each comprising two series of revoluble drums, strips connecting the drums of the two series and carrying signs similar to those of the drums of the sender, springs for returning the drums of the one series to their initial positions, ratchet-wheels rigidly connected with the drums of the other series, stationary pawls, electromagnets with rocking armatures, movable pawls linked to the rocking armatures, springs for detaching the armatures from the electromagnets and withdrawing the movable pawls from the ratchet-wheels, brakes for preventing the ratchet-wheels from shifting, and disengaging-electromagnets adapted to withdraw the stationary pawls from the ratchet-wheels, further parallel lines connecting in series the corresponding electromagnets of the several receivers with the corresponding shiftable contact-pieces of the sender, a common line connecting the parallel lines at their ends, branch lines connected with the contact-springs of the sender, another common line connecting the branch lines at their ends, a battery, lines connecting the battery with the two common lines, and parallel lines connecting in series the contact-pieces of the sender with the corresponding disengaging-electromagnets of the several receivers and with the one common line.

3. In an electrical station-indicating system, the combination with a frame, of a shaft in said frame, adjustable drums revoluble on said shaft and carrying signs on the periphery, scrolls each rigidly connected with one of said adjustable drums and having a plurality of concentric steps of consecutively-decreasing radius, an axle in said frame parallel to said shaft, counting-levers mounted to rock on said axle and each adapted to strike a step of one of said scrolls, springs pressing said counting-levers on said scrolls, toothed segments each rigidly connected with one of said counting-levers, movable pawls, means for periodically moving said movable pawls to feed said toothed segments one tooth after the other against the action of said springs, stationary pawls on said frame and adapted to ride over the teeth of said toothed segments, and contact-arms

each rigidly connected with one of said stationary pawls and adapted to periodically close a circuit, the whole forming a sender under the charge of a conductor.

- 5 4. In an electrical station-indicating system, the combination with a frame, of a shaft in said frame, adjustable drums revoluble on said shaft and carrying signs on the periphery, a rule on said frame for adjusting said adjustable drums, scrolls each rigidly connected with one of said adjustable drums and having a plurality of concentric steps of consecutively-decreasing radius, an axle in said frame parallel to said shaft, counting-levers mounted 15 to rock on said axle and each adapted to strike a step of one of said scrolls, springs pressing said counting-levers on said scrolls, toothed segments each rigidly connected with one of said counting-levers, an eccentric-shaft mounted to turn in said frame and carrying eccentric, movable pawls mounted

to turn on the eccentricities of said eccentric-shaft, a clockwork adapted for driving said eccentric-shaft to feed said toothed segments one tooth after the other against the action 25 of the springs, stationary pawls on said frame and adapted to ride over the teeth of said toothed segments, contact-arms each rigidly connected with one of said stationary pawls and adapted for periodically closing a circuit, and means controlled from said clockwork for simultaneously withdrawing said movable pawls and said stationary pawls from said toothed segments, the whole forming a sender under the charge of a conductor. 30 35

In testimony whereof I have signed my name to this specification in the presence of two subscribing witnesses.

JOSEF ESSER.
